MECHANISM FOR TRANSFERRING ARTICLES AND WRAPPERS TO TURRETS

Alfred German Rose, Gainsborough, England, assignor to Rose Brothers (Gainsborough) Limited, Gainsborough, England, a British company

Application May 1, 1947, Serial No. 745,277
In Great Britain May 16, 1946

6 Claims. (Cl. 93—7)

1

This invention relates to machines for wrapping sweets or other articles, the machines being of the same general kind (hereinafter referred to as the "kind described") as that described in United States Patent No. 1,735,978, granted to me November 19, 1929. The invention is particularly concerned with the mechanism for transferring the sweets from a feed support to the pockets of the movable carrier member. The specification mentioned above describes an apparatus in which a movable abutment is operable during the forward stroke of a transfer pusher to engage the rear face of the wrapper immediately behind the sweet, the abutment being spring-controlled and operated in such a manner that, during the transfer of the sweet across the gap between the feed table and the mouth of the receiving pocket, the sweet and its wrapper are resiliently gripped between the opposed faces of the pusher and the abutment.

It has been found, however, that the sweets, during wrapping, are apt to be crushed by impact with the abutment, particularly when they are slightly large. Also, when the sweets are slightly small, a further difficulty arises in that proper control is apt to be lost during its transfer. The difficulty of crushing becomes serious, particularly at high speed, when dealing with sweets consisting of a relatively thin and hard casing and a soft inside, since the casings of such sweets are apt to be very brittle.

According to the invention, these difficulties are considerably lessened if not entirely overcome, by providing a wrapping machine of the kind described, wherein the sweet-engaging tip of the movable abutment is attached to the body portion of the abutment by means of an intermediate portion of rubber or like material. The rubber portion is conveniently "bonded" to the remaining portions so that the abutment is, in effect, an integral whole. By these means, the sweet-engaging tip of the abutment is given an inherent resilience in addition to that resulting from the spring control of the abutment as a whole.

The abutment may, as described in the specification mentioned above, be made in two parts lying one on each side of the carrier member and so arranged that their sweet-engaging tips pass through the adjacent pocket of the carrier member during the transfer of the sweet into the pocket, the carrier member being so shaped that when the abutment is in its retracted position the pockets of the carrier member clear the abutment during rotation of the carrier member to bring

2

another pocket to the feeding station. Also, the two parts of the abutment may be combined for simultaneous movement with the rear wrapper-gripping elements in the same manner as that described in the above mentioned specification. In such a case, the rubber intermediate portion forms the connection between the abutment and the rear wrapper-gripping element. The sweet-engaging tips of such an abutment are set slightly in front of the plane containing the faces of the rear wrapper-gripping elements, e. g., by an amount equal to the difference between a sweet of normal width and one of minimum size within the range for which the apparatus is designed, so that the sweet-engaging tips of the abutment will be slightly deflected by a sweet of normal width when it reaches the normal plane of the wrapper feed.

It will be understood that the hardness of the rubber portion may vary between fairly wide limits according to the nature of the sweets intended to be wrapped. Thus, when wrapping caramels or the like, which are of a fairly tough nature, a fairly hard rubber may be used. On the other hand, when wrapping toffees consisting of a thin casing and a soft centre, quite a soft rubber may be necessary.

The invention will now be described in greater detail with reference to the accompanying drawings, in which

30 Figure 1 is an elevation of a portion of a machine for wrapping sweets.

Figure 2 is a plan view of the apparatus shown in Figure 1.

Fig. 3 is an enlarged fragmentary side view 35 illustrating the abutment tips.

Fig. 4 is an enlarged fragmentary plan view illustrating the abutment tips and cooperative gripping elements.

The machine is of the same general construction as that described in the above mentioned specification and it will only be necessary, therefore, to describe such constructional features as are necessary for a clear understanding of the present invention, reference being made to the 40 above mentioned specification for further details.

Referring to the drawings, sweets 11 are transferred in succession from a feed channel 12 to successive pockets of a carrier member 13 by a reciprocating pusher 14, the carrier member 13 being intermittently rotated in timed relationship with the movement of the pusher 14. Between each stroke of the pusher 14, a wrapper 16 is fed into a position between the sweet about to be transferred and the adjacent pocket of the carrier member 13 so that the sweet 11 and wrapper

16 are together pushed into the adjacent pocket of the carrier member 13, the wrapper 16 being partially folded about the sweet during such movement.

Arranged between the feed channel 12 and the adjacent pocket of the carrier member 13 (assuming the carrier member to be stationary in the sweet-receiving position) are two pairs of wrapper-gripping elements disposed one pair on each side of the carrier member 13, each pair consisting of a rear gripping element 17 and a front gripping element 18. The front gripping elements 18 are each constituted by a batch of thin leaf springs and each element is carried on an arm 19 extending from a boss 21 freely mounted on a common shaft 22, the two bosses 21 being connected for simultaneous motion by a bridge piece 23. One of the bosses 21 is provided with an arm 24 on which is freely mounted a cam roller 26 arranged to bear against the face of a rotatable cam 27 mounted on a cam shaft 28, the roller 26 being maintained in engagement with the surface of the cam 27 by means of a spring 29.

The rear gripping elements 17 are mounted on arms 31 extending from a common supporting member 32 freely mounted on the shaft 22, the supporting member 32 being provided with an arm 33 on which is freely mounted a cam roller 34 arranged to bear against the face of a rotatable cam 36 secured to the cam shaft 28. The cam roller 34 is maintained in engagement with the cam 36 by means of a spring 37.

Arranged in the path of movement of the sweets 11 during their transfer from the feed channel 12 to the carrier member 13, is an abutment consisting of two abutment parts 41 attached respectively to the rear gripping elements 17 by means of intermediate portions 42 of rubber, the intermediate portions 42 being provided with tongues 43 which are let into correspondingly shaped recesses in the parts 17 and 41, respectively. The intermediate portions 42 are "bonded" to the parts 41 and elements 17, respectively, so that each part 41 and the corresponding element 17 are, in effect, an integral whole.

The timing of the apparatus is such that, at the same time as, or slightly before, the forward edge of the sweet 11 reaches the plane of feed of the wrappers 16 under the action of the pusher 14, a wrapper 16 is gripped between the front and rear gripping elements 18 and 17, and the forward face of the sweet 11 strikes the two abutment parts 41 with the wrapper 16 disposed between the sweet and the abutment parts. During the movement of the sweet 11 from that position into the adjacent pocket of the carrier member 13, the sweet 11, abutment parts 41, and the front and rear elements 18 and 17, all move together with the wrapper 16 resiliently gripped between the front face of the sweet 11 and the abutment parts 41 and also between the gripping elements 17 and 18.

The sweet-engaging tips of the abutment parts 41 are set in front of the plane containing the faces of the rear elements 17 by an amount equal to the difference between a sweet of normal width and one of minimum size within the range for which the apparatus is designed, so that the abutment parts 41 will be slightly deflected by a sweet of normal width when it reaches the normal plane of feed of the wrappers, while a sweet of minimum width will be just gripped between the pusher 14 and the abutment parts 41. It will thus be seen that full control of the sweet is exercised

during its transfer from the feed channel 12 to the pocket of the carrier member 13 despite possible slight variation in the width of successive sweets.

5 The cams 27 and 36 are so shaped and timed that, as soon as the toffee 11 is positioned in the pocket of the carrier member 13, the arms 31 move further forward towards the axis of the carrier member 13 so as to move the abutment parts 41 clear of the jaws of the pockets, while the arms 19 are caused to move in the opposite direction so as to cause the front elements 18 to clear the path of movement of the partially folded wrapper in the pocket of the carrier member 13 during the movement of that member to bring the next succeeding pocket to the feeding position, when the cycle of operations is repeated.

I claim:

1. A wrapping machine comprising a feed support, a movable carrier member, means for transferring the articles to be wrapped in succession from said support to separate pockets in said carrier member, means for feeding wrappers successively across the mouths of said pockets so that the wrappers are carried forward with the articles into said pockets, and a movable abutment comprising an article-engaging tip between which and said transferring means the articles and wrappers are gripped as they are transferred, a body portion and an intermediate portion of rubber or like material connecting the end of said tip opposite to the article-engaging portion thereof to the body portion, said end being remote from the article-engaging portion so that the tip constitutes a resilient arm.

2. Apparatus according to claim 1, wherein the rubber portion is "bonded" to the article-engaging tip and the body portion.

3. Apparatus according to claim 2, wherein the abutment is made in two parts lying one on each side of the carrier member and each comprising an article-engaging tip connected to a body portion by an intermediate portion of rubber or like material, the article-engaging tips being so arranged that they pass through the adjacent pocket of the carrier member during the transfer of the article to the pocket.

4. Apparatus according to claim 1, wherein the abutment is made in two parts lying one on each side of the carrier member and each comprising an article-engaging tip connected to a body portion by an intermediate portion of rubber or like material, the article-engaging tips being so arranged that they pass through the adjacent pocket of the carrier member during the transfer of the article to the pocket.

5. A wrapping machine comprising a feed support, a movable carrier member, means for transferring the articles to be wrapped in succession from said support to separate pockets in said carrier member, means for feeding wrappers successively across the mouths of said pockets so that the wrappers are carried forward with the articles into said pockets, a movable abutment comprising a pair of article-engaging tips lying one on each side of the carrier member and between which and said transferring means the articles and wrappers are gripped as they are transferred, a pair of body portions and a pair of intermediate portions of rubber or like material, each connecting the end of a tip opposite to the article-engaging portion thereof, to a body portion, said end being remote from the article-engaging portion of the tip so that the tips each constitute a resilient arm, the tips being so ar-

ranged that they pass through the adjacent pockets of the carrier member during the transfer of the articles to the pocket, and front and rear wrapper-gripping elements between which each wrapper is gripped during the transferring action, said rear gripping elements being constituted by parts of the body portion of the abutment.

6. Apparatus according to claim 5, wherein the article-engaging tip of the two parts of the abutment member are set slightly in front of the plane containing the bases of the rear wrapper-gripping elements.

ALFRED GERMAN ROSE.
